UNITED STATES PATENT OFFICE.

WILLIAM M. BRADSHAW AND ALMON W. COPLEY, OF WILKINSBURG, PENNSYLVANIA,
ASSIGNORS TO WESTINGHOUSE ELECTRIC AND MANUFACTURING COMPANY, A COR-
PORATION OF PENNSYLVANIA.

WATTMETER.

1,194,129.

Specification of Letters Patent.

Patented Aug. 8, 1916.

Application filed March 9, 1912. Serial No. 682,797.

To all whom it may concern:

Be it known that we, WILLIAM M. BRADSHAW and ALMON W. COPLEY, citizens of the United States, and residents of Wilkinsburg, in the county of Allegheny and State of Pennsylvania, have invented a new and useful Improvement in Wattmeters, of which the following is a specification.

Our invention relates to wattmeters and similar motormeters for use in connection with alternating current circuits, and it has for one of its objects to provide a wattmeter having an exceptionally high degree of accuracy in operation over a wide range of fluctuations of voltage, load, power factor and frequency, and which is also exceedingly simple, compact and light in construction.

A further object of our invention is to provide highly effective and convenient means for adjusting the compensation for friction.

Our invention is illustrated in the accompanying drawings, Figure 1 of which is a front face view of a wattmeter that is constructed in accordance therewith, a part of the cover and certain other parts thereof being broken away for the sake of clearness of illustration. Fig. 2 is a view, partially in side elevation and partially in section, of the meter of Fig. 1. Fig. 3 is a face view of the principal operating parts of the meter with the circuit connections thereof shown diagrammatically. Fig. 4 is a plan and sectional view of the core or magnetic circuit of the meter along the line IV—IV of Fig. 3, and Fig. 5 is a partial plan view of the armature and magnetic circuit showing their relations to each other.

The operating parts of the meter are mounted within a base or box 1 for which a removable cover 2 is provided, the said operating parts comprising a laminated electromagnet or core member 3, that is secured to bosses or seats 4 upon the bottom inner face of the base by means of tap bolts 5, which also serve to secure an iron cover 6 in position over the outer face of the electromagnet for shielding the same from external magnetism. The main portion of the electromagnet 3 is substantially the form

of the core member of a transformer of the shell type and comprises a central member or leg 7 that is joined at one end to two outer legs or yokes 7^a and is separated therefrom at its other end by short curved air gaps 8, a suitable rectangular winding space being provided between the middle and the outer legs. Each of the legs of the electromagnet is extended at the side thereof that is provided with air gaps to form poles that are disposed adjacent to a rotatable conducting disk 9 constituting the armature or movable element of the meter. The corner portions of the extended pole faces are located substantially opposite to the edge of the armature, as shown in Fig. 5.

An arm 11, that is integral with the base and extends forwardly therefrom, is provided with a plane surface directly opposite the poles of the electromagnet, the disk 9 being interposed between the said surface and the electromagnet. The extension of the central leg 7 of the magnet is provided with a partially inclosed slot 8^a near its polar extremity, the outer end of the slot being preferably only of sufficient width to permit of the insertion of the wires of coils to be hereinafter described. The outer legs 7^a are provided with lateral extensions 13 which constitute pole shoes and serve to enlarge the polar area of the magnet.

The central leg of the electromagnet is provided with a potential winding 14 that is adapted to be connected in shunt to, or between the conductors of, the circuit 15—16 in connection with which the instrument is employed for the purpose of measuring the energy traversing it. The polar extremities of the legs of the electromagnet are provided with two series or load coils 17 that occupy a slot 8^a in the end of the central leg and the spaces behind the pole shoes 13 on the other legs, and respectively surround parts of the middle leg and the outer legs 9 and also span the air gaps between them, the said coils being connected in series with one of the conductors 16 of the circuit 15—16, or being otherwise supplied with current that is proportional to the current traversing the said circuit.

The movements of the rotatable disk 9 are

retarded by means of a permanent magnet 18 that is carried by a post 19 which is formed integral with, and extends forward from, the base. The polar extremities of the 5 magnets are disposed adjacent to the disk and are opposite an armature 20 that is located upon the other side of the disk and is carried by the arm 11. The armature 20 is mounted upon a stud 21 that is screwed into 10 the arm 11, so that its distance from the permanent magnet and the disk may be adjusted for the purpose of regulating the degree of damping afforded by the permanent magnet, a set screw 22 being provided for securing the armature in its adjusted position.

Adjustable means are also provided for compensating for friction or light load, the 15 said means comprising two formed sheet metal closed-circuit conductors 23 that are 20 pivotally mounted upon bolts 24 which extend through holes in the electromagnet core and assist in securing the laminæ together. The inner ends of the conductors 23 are located and movable in the curved air gaps 8 25 between the central and outer legs of the electromagnet. The closed-circuit conductors 23 are connected together for simultaneous rotative movement by means of a bar 25 having slots through which the bolts 24 project, auxiliary nuts or studs 26 and 27 that 30 project through the cover 6, being screwed upon the front ends of the said bolts. The bar 25 carries two pins 28 that project into apertures in lugs 29 that are formed integral 35 with the closed-circuit conductors. One end of the bar 25 is bent forward substantially parallel to the nut 26 and is provided with an aperture to receive a screw 30 that is 40 screwed into the side of the nut 26 and is surrounded by a helical compression spring 31 for forcing the laterally bent end of the bar against the head of the screw. Thus, by 45 turning the screw 30, the positions of the ends or portions of the closed-circuit conductors that are located in the air gaps of the electromagnet are varied, the said ends of the closed-circuit conductors being moved in opposite directions. The outer face of 50 the laterally bent end of the bar 25 is provided with an arrow and with letters S and F to indicate the directions of rotation of the screw 30 for causing the meter to run either slow or fast. (See Fig. 2). To insure 55 against lost-motion between the closed-circuit conductors 23 and the pins 28, helical springs 32 surround the supporting bolts 24 and have extensions that respectively engage the ends of the closed-circuit conductors and the core member 7^a. (See Figs. 3 and 4).

60 The nut or stud 27 serves to lock the parts in any position to which they may be adjusted.

In order that the meter may be accurate with changes in the power factor of the cir-

cuit in connection with which it is employed, the polar end of the middle leg of the electromagnet is surrounded by a closed-circuit conductor or coil 33 that is adjustable vertically or longitudinally of said leg, or the resistance of which is variable in any suitable manner.

70

The peculiarities of construction of the present meter which we regard as important, are the placing of the potential winding and the total load windings upon the same magnetizable core or magnet and upon one side 65 only of the rotatable disk, with the load coils surrounding polar extensions of, and the air gaps between, the legs of the magnet. By this arrangement, a high degree of alternating polarization is secured which renders 75 the meter exceedingly sensitive to changes of current in the load coils and consequently very accurate, even upon very light loads. The lateral extensions or shoes upon the polar members are also important, in that 80 they enlarge the areas of the pole faces and effect an advantageous distribution of the fluxes. Moreover the disposition of the outwardly extending horns 13 in close proximity to the edge of the armature, cask 90 9, results in the production of eddy currents of relatively low value in the armature by reason of the relatively long and consequently high resistance paths which the eddy currents are forced to traverse. Thus the 95 damping eddy currents are decreased when the load is increased and substantial accuracy of the meter registrations is maintained throughout the entire range of operation.

The amounts of both iron and copper in 100 the present device are also very small as a result of the peculiarities of construction above set forth. The meter is consequently light, compact and inexpensive. Furthermore, adjustments for friction or light load may be 105 readily and conveniently effected by the proper rotation of a single screw for which directions are given adjacent to the screw so that no confusion will be likely to occur.

We are aware that it is old to provide a 110 meter with a magnetizable core comprising a middle leg surrounded by the potential coil and outer legs that are separated at one end from the middle leg by small air gaps with a part of the series winding surrounding the separated ends of the core legs, but in all such meters with which we are 115 familiar an additional part of the series winding is provided upon the opposite side of the rotatable disk. Furthermore, the 120 polar faces of the cores of such prior structures have not been enlarged by the provision of lateral extensions or shoes upon the poles, resulting in different flux distributions from that obtained by the present 125 structure. We, of course, make no claim to

such prior structures, but have carefully distinguished our invention from them.

While the present device is particularly adapted to the measurement of energy, it is primarily a motor, and we accordingly intend that the appended claims should be construed to include all motors coming within their terms, irrespective of the purposes for which they are employed.

10 Although the specific form of construction shown has been found highly effective and is that which is preferred, it is obvious that many modifications may be made thereof within the spirit of the invention, and 15 we desire to include all such modifications within the scope of the appended claims.

We claim as our invention:

1. An alternating current motor-meter comprising a rotatable disk, a magnetizable 20 core having polar members that are separated by a small air gap, certain of said polar members being provided with a laterally extending horn to permit proximate relationship between the polar surface of the 25 core and the edge of the disk, whereby the torque of the meter is increased and substantial accuracy of its registrations is maintained, a potential coil upon the core, and a series winding surrounding the separated 30 portions of the polar members behind the horn and constituting the total series winding of the meter.

2. An alternating current motor-meter comprising an armature, a magnetizable 35 core having polar members that are separated by small air gaps and are disposed adjacent to one side only of the armature, certain of said polar members being provided with laterally extending horns, whereby corner portions of the poles are brought substantially opposite to the edge of the armature, a potential coil upon the core, and a series winding surrounding the separated 40 portions of the polar members behind the horns and constituting the total series winding of the meter.

3. An alternating current motor-meter comprising a rotatable disk, a magnetizable core having a central member and side members joined to one end of the central member and separated from its other end by small air gaps, the central member being provided with a slot in its free end and the free ends of the side members being provided 55 with lateral extensions to permit proximate relationship between the polar surface of the core and the edge of the disk, whereby the torque of the meter is increased and substantial accuracy of its registrations is maintained, a complete series winding partially 60 located in the slot in the central member and surrounding the adjacent ends of the side members, and a potential coil upon the core,

4. An alternating current motor-meter comprising a magnetizable core having a 65 central member and side members joined to one end of the central member and separated from its other end by small air gaps, the central member being provided near its free end with a slot that is partially closed and the free ends of the side members being provided with lateral polar extensions that project outwardly, a series winding partially located in the slot in the central member and surrounding the adjacent free ends 70 of the side members, the said winding constituting the total series winding of the meter, and a potential coil upon the core.

5. In an alternating current motor-meter, the combination with a magnetizable core 80 having a central member and side members separated therefrom at one end by air gaps, of two closed-circuit conductors having sides movable respectively in said air gaps, and means for simultaneously but oppositely adjusting the positions of the said sides of the conductors in the air gaps.

6. In an alternating current motor-meter, the combination with a magnetizable core 90 having a central member and side members separated therefrom at one end by air gaps, of two closed-circuit conductors having sides movable respectively in said air gaps, and means for simultaneously adjusting the positions of the said sides of the conductors in 95 the air gaps.

7. An alternating current motor-meter comprising a rotatable disk, a magnetizable core having polar members that are separated by small air gaps, certain of said polar 100 members being provided with laterally extending horns so disposed that an increased resistance of the eddy current path in the disk is effected, whereby the torque of the meter is increased and substantial accuracy 105 of its registrations is maintained, a potential coil on the core, and a series winding surrounding the separated portions of the polar members behind the horns and constituting the total series winding of the 110 meter.

8. An alternating current motor-meter comprising a rotatable disk, a magnetizable core having polar members that are separated by small air gaps, certain of said polar 115 members being provided with laterally extending horns disposed in proximity to the edge of the disk, a potential coil upon the core, and a series winding surrounding the separated portions of the core members behind the horns and constituting the total 120 series winding of the meter.

9. In an alternating current motor-meter, the combination with a rotatable disk, and a magnetizable core comprising polar members 125 that are separated by small air gaps

and a plurality of laterally extending horns whereby the portions of the core adjacent to the edge of the disk are in close proximity thereto, of a potential coil upon the core and 5 a series winding surrounding the separated portions of the polar members and constituting the total series winding of the meter. In testimony whereof, we have hereunto

subscribed our names this 24th day of February, 1912.
